UNITED STATES PATENT OFFICE.

JOHN SAVOY, OF BOSTON, MASSACHUSETTS.

SEINE-PURSING APPARATUS.

SPECIFICATION forming part of Letters Patent No. 784,010, dated February 28, 1905.

Application filed May 23, 1904. Serial No. 209,194.

To all whom it may concern:

Be it known that I, JOHN SAVOY, a citizen of the United States of America, and a resident of Boston, in the county of Suffolk and State of Massachusetts, have invented certain new and useful Improvements in Seine-Pursing Apparatus, of which the following is a specification.

This invention relates to seine-pursing apparatus, and has for its object the production of a simple, durable, and efficient device for drawing in the purse-lines or bridle of a purse-seine; and it consists in certain novel features of construction and arrangement of parts which will be readily understood by reference to the description of the drawings and to the claims to be hereinafter given.

Of the drawings, Figure 1 represents a plan view of a seine-pursing apparatus embodying the features of this invention. Fig. 2 represents a side elevation of the same. Fig. 3 represents an end elevation of the same. Fig. 4 represents a section on line 4-4 on Fig. 1, showing the sheave-operating device; and Fig. 5 represents a detail of the bight-forming devices.

Similar characters designate like parts throughout the several figures of the drawings.

In the drawings, 10 represents a base-plate provided with vertical frames 11, 11, which frame supports bearings 12, in which is mounted a revoluble shaft 13, which has secured to either end outside of said bearings 12 a rope-hauling sheave 14. Secured to the inner sides of each sheave 14 is a ring 15, provided on its outer periphery with a plurality of teeth 16, with which the tooth 17 of the weighted pawl 18 engages. The pawl 18 is pivoted at 19 to an arm 20, loosely mounted upon the revoluble shaft 13 between the hub 40 of the sheave 14 and the bearings 12. The outer end of each arm 20 is connected by a link 21 to a walking-beam 22, pivotally supported at 23 substantially midway its ends parallel to the shaft 13 on a standard 24, the ends of which are secured to the vertical frames 11 and serve as a tie between the same. The walking-beam 22 is provided with suitable sockets 25, in which handles 26 may be inserted and secured in position by means of pins 27, all in a well-known manner.

The boat in which the apparatus is mounted

is provided with a cross-support 28, which may be a seat or other member, as desired. To the side walls of the support 28 are secured plates 29, provided with studs or projections 30, with which the notches 31 in the plates 32, secured to the sides of the vertical frames 11, coact to lock the apparatus in operative position. The notches 31 are open toward the side of the boat from which the bridle of the purse-seine is operated, so that any strain upon the apparatus will cause the notches 31 to coact with the projections 30 to secure a firmer hold thereon. When in operative position, a pin 33, secured by a chain 34 to an eye 35, is inserted into the support 28 at the rear of the plate 32 to prevent the apparatus from being accidentally moved along the support 28 to unlock the same. At each end of the apparatus a handle 34 is provided, connecting the vertical frames 11, 11 and by which the apparatus may be readily removed from position when it is desired to use the same for storage in the bottom of the boat. One side of the boat is provided with a davit 35, having laterally-projecting arms 36, from which depend blocks 37 in front of and in line with the sheaves 14. The purse-line 38 passes from the seine through the block 37, partially around the sheave 14 and then over the smaller 80 sheave 39 of the bight-forming devices, and then is coiled up in the bottom of the boat in a well-known manner. The smaller sheave 39 is mounted in a forked arm 40, pivoted at 41 to brackets 42, projecting laterally from the 85 ends of the vertical frames 11. A spring 43 connects the forked arm 40 with a stationary part and holds the sheave 39 in position in the groove of the sheave 14. The arm 40 is provided with an extension 44, the upper 90 end of which is provided with a lateral projection 45, which straddles the sheave 14 and has mounted therein a roller 46, which extends to the bottom of the groove in the sheave 14. The object of the roller 46 is to prevent the 95 purse-line 38 from passing around the sheave 14 and insuring its remaining upon the bight-forming sheave 39, thereby forming a bight and holding the lines against retractive movement. The springs 43 will have sufficient resistance to form purse-line-holding bights, but not a sufficient resistance to prevent the levers

40 being withdrawn downward by a pull on that portion of the line in advance of said levers.

The walking - beam operates through the 5 connectors 21 to alternately operate the pawl-carrying arms 20 to effect a movement of the sheaves 14 in the proper direction to indraw the purse-line when desired, the effective operation being produced by the down movement of either end of the walking-beam, whereby more power is secured than would be the case in devices as heretofore provided when the effective operation of the sheaves has been produced by the up movement of the walking-beam. The walking - beam is pivotally supported in a plane parallel with the shaft 13, so that the operators may stand where they will in no wise interfere with the coiling and storing of the ends of the purse-lines.

20 It is believed that with the foregoing description the operation of the invention will be thoroughly understood.

Having thus described my invention, I claim—

25 1. In a seine-pursing apparatus for use in a seine-boat and to be operated in connection with crane-supported tackle-blocks for guiding and controlling the purse-lines of a seine, the combination with a bed-plate having vertical frames, of a revoluble shaft supported in bearings on said frames, a sheave secured to either end of said shaft, a ratchet-wheel secured to either sheave, arms loosely mounted on said shaft, a pawl secured to either arm and adapted to engage with said ratchet-wheel, a walking-beam, and means for connecting said beam with said pawl-carrying arm.

2. In a seine-pursing apparatus for use in a seine-boat and to be operated in connection 40 with crane-supported tackle-blocks for guiding and controlling the purse-lines of a seine, the combination with a bed-plate having vertical frames, of a revoluble shaft supported in bearings on said frames, a sheave secured to either end of said shaft, a ratchet-wheel secured to either sheave, arms loosely mounted on said shaft, a pawl secured to either arm and adapted to engage with a ratchet-wheel, a walking - beam supported for oscillatory 45 movements in a plane parallel to the axis of said shaft, and means for connecting said beam with said pawl-carrying arm.

3. In a seine-pursing apparatus for use in a seine-boat and to be operated in connection 55 with crane-supported tackle-blocks for guiding and controlling the purse-lines of a seine, the combination with a bed-plate having vertical frames, of a revoluble shaft supported in bearings on said frames, a sheave secured to either end of said shaft, a walking-beam supported for oscillatory movements in a plane parallel to the axis of said shaft, and two alternately effective pawl-and-ratchet devices for operative connection with said shaft 60 and walking-beam.

4. In a seine-pursing apparatus for use in a seine-boat and to be operated in connection with crane-supported tackle-blocks for guiding and controlling the purse-lines of a seine, the combination with a bed-plate having vertical frames, of a revoluble shaft supported in bearings on said frames, a sheave secured to either end of said shaft, a ratchet-wheel secured to either sheave, a walking-beam supported for oscillatory movements in a plane 75 parallel to the axis of said shaft, pawl-carriers connected to said walking-beam at opposite sides respectively of the axis of oscillation thereof, and pawls mounted on the pawl-carriers in position to engage the teeth of the 80 ratchet-wheels.

5. In a seine-pursing apparatus to be used in a seine-boat, the combination with a bed-plate having vertical frames, of a shaft supported in bearings on said frames, two sheaves fixed to opposite ends of said shaft, a ratchet-wheel secured to each of said sheaves, a tie-girth connecting said frames, a walking-beam supported on said tie-girth for oscillatory movements in a plane parallel to the axis of said shaft, 85 pawl-carriers connected to said walking-beam at opposite sides respectively of the axis of oscillation thereof, pawls mounted on the pawl-carriers in position to engage the teeth of the ratchet-wheels, a davit mounted on the side of 90 the boat, and seine-blocks supported by said davit and in substantial horizontal alinement with the upper peripheral portion of said 95 sheaves.

6. In a seine-pursing apparatus for use in a seine-boat and to be operated in connection with crane-supported tackle-blocks for guiding and controlling the purse-lines of a seine, the combination with a bed-plate having vertical frames, of a revoluble shaft supported in bearings on said frames, a sheave secured to either end of said shaft, a tie-girth connecting said frames, a walking-beam supported on said tie-girth for oscillatory movements in a plane parallel to the axis of said shaft, and means connecting said walking-beam with 100 said driving-shaft and effective for driving the same.

7. In a seine-pursing apparatus for use in a seine-boat and to be operated in connection 105 with crane-supported tackle-blocks for guiding and controlling the purse-lines of a seine, the combination with a bed-plate having vertical frames, of a shaft supported in bearings on said frames, two sheaves fixed to opposite 110 ends of said shaft, a ratchet-wheel secured to each of said sheaves, a tie-girth connecting said frames, a walking - beam supported on said tie-girth for oscillatory movements in a plane parallel to the axis of said shaft, pawls coacting with said ratchet-wheels for driving said 115 shaft, and connectors between said walking-beam and said pawls and effective for operating the same.

8. In a seine-pursing apparatus for use in a 120

seine-boat and to be operated in connection with crane-supported tackle-blocks for guiding and controlling the purse-lines of a seine, the combination with a bed-plate having vertical frames, of a shaft supported in bearings on said frames, two sheaves fixed to opposite ends of said shaft, a ratchet-wheel secured to each of said sheaves, a tie-girth connecting said frames, arms loosely mounted upon said shaft, a walking-beam supported on said tie-girth for oscillatory movements in a plane parallel to the axis of said shaft, connectors between said arms and said walking-beam, and weighted pawls pivoted to said arms and coöperating with said ratchet-wheels to drive said shaft.

9. In a seine-pursing apparatus for use in a seine-boat and to be operated in connection with crane-supported tackle-blocks for guiding and controlling the purse-lines of a seine, the combination with a bed-plate having vertical frames, of a shaft supported in bearings on said frames, two sheaves fixed to opposite ends of said shaft, a spring-controlled pivoted arm opposite each sheave, a purse-line sheave therein and a roller mounted in bearings in the free end of said pivoted arm beyond said sheave and projecting into the groove of said sheave.

10. In a seine-pursing apparatus for use in a seine-boat and to be operated in connection with crane-supported tackle-blocks for guiding and controlling the purse-lines of a seine, the combination with a bed-plate having vertical frames, of a shaft supported in bearings on said frames, two sheaves fixed to opposite ends of said shaft, and a spring-controlled pivoted lever provided with a forked end straddling each sheave.

11. In a seine-pursing apparatus for use in a seine-boat and to be operated in connection with crane-supported tackle-blocks for guiding and controlling the purse-lines of a seine, the combination with a bed-plate having ver-

tical frames, of a shaft supported in bearings on said frames, two sheaves fixed to opposite ends of said shaft, a spring-controlled pivoted lever provided with a forked end straddling each sheave, and a roller mounted in the forked end and projecting into the groove of said sheave.

12. In a seine-pursing apparatus for use in a seine-boat, the combination with a bed-plate, of a revoluble shaft, sheaves mounted on either end of said shaft, means for revolving said sheaves, notched plates secured to either side of said bed-plate, and projections secured to said seine-boat coöperating with the notches in said side plates.

13. In a seine-pursing apparatus for use in a seine-boat, the combination with a bed-plate, of a revoluble shaft, sheaves mounted on either end of said shaft, means for revolving said sheaves, notched plates secured to either side of said bed-plate, projections secured to said seine-boat coöperating with the notches in said side plates, and means for preventing the removal of said plates from engagement with said projections.

14. In a seine-pursing apparatus for use in a seine-boat, the combination with a bed-plate, of a revoluble shaft, sheaves mounted on either end of said shaft, means for revolving said sheaves, notched plates secured to either side of said bed-plate, projections secured to said seine-boat coöperating with the notches in said side plates, and handles secured to either end of said bed-plate to move said mechanism into and out of engagement with said projections.

Signed by me at Boston, Massachusetts, this 26th day of April, 1904.

JOHN SAVOY.
